The ornamental design for a sign support, as shown and described.

DESCRIPTION

FIG. 1 is a perspective view of a transparent sign support with broken lines showing the sign support mounted to a shelf post. FIG. 2 is a perspective view of the transparent sign support in an unassembled configuration as a single piece according to one embodiment.

FIG. 3 is a top view of the transparent sign support in the unassembled configuration as a single piece according to one embodiment.

FIG. 4 is a perspective view of the transparent sign support showing the end portion separated from the main body in a first assembled position of use.

FIG. 5 is a front view showing the first assembled position of the transparent sign support.

FIG. 6 is a top view showing the first assembled position of the transparent sign support.

FIG. 7 is a bottom view showing the first assembled position of the transparent sign support.

FIG. 8 is a left side view showing the first assembled position of the transparent sign support.

FIG. 9 is a right side view showing the first assembled position of the transparent sign support.

FIG. 10 is a back view showing the first assembled position of the transparent sign support.

FIG. 11 is a perspective view of the transparent sign support showing the end portion separated from the main body in a second assembled position of use.

FIG. 12 is a perspective view of the transparent sign support showing the end portion separated from the main body in a third assembled position of use.

FIG. 13 is a perspective view according to a second non-transparent embodiment of the sign support showing the end portion separated from the main body in a first assembled position of use.

FIG. 14 is a front view of the unassembled non-transparent sign support.

FIG. 15 is a top view showing the first assembled position of the non-transparent sign support.

FIG. 16 is a bottom view showing the first assembled position of the non-transparent sign support.

FIG. 17 is a left side view showing the first assembled position of the non-transparent sign support.

FIG. 18 is a right side view showing the first assembled position of the non-transparent sign support; and,

FIG. 19 is a back view showing the first assembled position of the non-transparent sign support.

In the drawings, the broken lines illustrate the environment in which the sign support is used and forms no part of the claimed design.
